MERCURY SWITCH

Charles W. Trautman and Herbert E. Bucklen,
III, Elkhart, Ind., assignors to Bucklen-Bear
Laboratories, Inc., Elkhart, Ind., a corporation
of Indiana

Application July 26, 1940, Serial No. 347,678

7 Claims. (Cl. 209—152)

This invention relates to mercury switches, and more particularly is directed to the metal envelope type of mercury switch incorporating means for assisting in the making of the circuit through the switch by means of a primary electrode contact member formed of a material which is substantially unaffected by the constant arcing usually found in a switch of the metal to mercury contact type.

In the majority of metal envelope mercury switches with which I am familiar, it has been found desirable to provide an iron electrode which, in turn, is constantly engaged by a retained body of mercury so that upon making or breaking of the circuit, the arcing will occur between the retained body and a moving body of mercury to shield the metal electrode from the arcs occurring during the switching operations. This has been considered desirable since the mercury arcs impinging on the iron electrode have been found to reduce the life of the switch so that it will withstand only about one-fourth the number of contacts that a switch of the positive mercury to mercury contact type is capable of withstanding. However, there are certain advantages in a direct metal to mercury type of contact insofar as snap action switches are concerned, and also in switches which may be employed as drop-cord switches or level devices in which a narrow angle is desired.

The present invention contemplates providing the electrode with an axially inwardly extending disc portion formed of a material such as tungsten, molybdenum, or tantalum, which will take the initial arcing when contact is made or broken in the switch, and which is not seriously affected by such arcs due to the characteristics of the metal employed.

This simplifies the internal construction of the switch to a considerable extent, since the ceramic may be of simple formation without requiring an undercut or groove for the retained body of mercury, and the electrode construction can be simplified to a considerable extent. The disc of arc resisting material is preferably so arranged with respect to the throat or passageway of the ceramic interposed between the envelope and the electrode as to provide a means for preventing splashing of the mercury during snap action, and provides a control capable of insuring positive, clean breaking of the circuit with no secondary arcing or the like. The arc resisting electrode disc serves as a baffle or damper to prevent surging of the mercury and possible intermittent or secondary contacts

thereof with the electrode, which would be the case if the primary disc were not located in the particular position provided.

Another feature of the present invention is the provision of a very simple form of switch structure in which a tungsten or molybdenum shank is projected inwardly from the electrode, and is used as the contact means for the movable body of mercury. This shank or pin may be secured to the main electrode stud in any suitable manner, such as by a press fit, threading, or staking the same into position.

Other objects and advantages of the present invention will be more apparent from the following detailed description which, taken in conjunction with the accompanying drawings, will disclose to those skilled in the art the particular construction and operation of a preferred form of the present invention.

In the drawings:

Figure 1 is a vertical sectional view through a narrow angle snap action type of switch construction embodying the present invention;

Figure 2 is a corresponding sectional view through a switch normally employed as a drop-cord switch or level indicating type of switch;

Figure 3 is a sectional view through a modified form of switch provided with an enclosing insulating case; and

Figures 4 to 8, inclusive, are sectional views through still further modified forms of switch structure embodying the present invention.

Referring now in detail to Figure 1, we have provided a switch envelope 5 of generally elongated cup-shape form having the open end portion 6 which is internally bored to provide the radial shoulder 7 adjacent the end. The envelope 5 may be formed of any suitable material, such as cold rolled stock or the like.

Seated against the radial shoulder 7 and centered in the counterbored portion 6 of the envelope 5 is a ceramic insert 8 which is provided with the frusto-conical throat portion 9 terminating in a radially extending shoulder 10 against which is seated the electrode disc 12. The disc 12 is formed of iron or the like, and is thereby centered in and supported by the ceramic insert 8. The rear face of the electrode disc, as well as the rear or outer end of the insert 8, is engaged by a resilient sealing member 13, preferably formed of rubber or the like and having the peripheral flange or skirt 14 overlying a tapered shoulder on the outer end of the ceramic to provide an effective seal between the electrode and ceramic and between the ceramic and the in-

ternal wall of the open end of the switch. The sealing member 13 extends about the shank portion 15 of the electrode, which shank portion extends through the electrode and is provided with a shoulder holding the electrode in engagement with the radial shoulder 10 of the ceramic and provided with the reduced inwardly extending portion 16 which, at its inner end carries a metallic disc 17 of a diameter such that it provides a slight annular opening between its periphery and the internal surface of the envelope 5. The extending portion 16 of the electrode shank 15 is provided with a punched over portion 18, which serves to lock the electrode disc 12 against axial movement relative to the shank.

A suitable refractory compression member 19 engages the outer face of the sealing means 13 and holds the same under compression, this stress being exerted through the compression member 19 by means of the spun-over end 20 of the envelope which holds the retaining washer 22 firmly against the rear face of the compression member. This compression member preferably has a reduced cylindrical extension 23 forming an insulating barrier between the spun-over edge of the envelope and the shank of the electrode.

The disc 17 carried at the inner end of the electrode shank is disposed slightly forwardly of the inner end of the ceramic 8, and is preferably formed of a material which is resistant to mercury arcs, such as tungsten, molybdenum or tantalum. A body of mercury 24 is introduced into the interior of the envelope after the electrode and sealing means has been assembled in position within the envelope through the tubulation 25, which tubulation then serves for evacuating the switch chamber 26 and filling the same with an inert gas under pressure, such as hydrogen. The tubulation is then pinched closed and welded as indicated at 27 to seal the interior of the switch.

In the operation of the structure thus far described, it will be apparent that when the switch is tilted in a counterclockwise direction the body of mercury 24 runs along the inner surface of the envelope 5 into contact with the disc 17, and will then be extruded through the annular gap between the periphery of the disc and the envelope and up the throat 9 of the insert into secondary contact with the electrode 12. However, the circuit is made or broken when the body of mercury 24 contacts the disc 17, and consequently any arcing that may occur will occur between the mercury and the disc 17. Inasmuch as the disc is formed of an arc resisting metal, this will have no detrimental effect upon the disc. However, the position of the disc and its relation to the interior of the envelope and the ceramic insures that the mercury when moving toward the disc will be trapped thereby on the rear face of the disc, and consequently will not have any splashing or vibrating action which might cause intermittent operation of the switch. As a result, a positive making and breaking of the circuit is provided with no secondary arcing or sputtering, the primary disc 17 serving as a primary contact member, and also as a baffle or dampening means for insuring positive contact and positive breaking of the circuit without any secondary arcing, such as would be the case if the disc were removed and the body of mercury allowed to run up the incline and impinge directly upon the electrode 12. There would be the possibility of it producing either a narrow forwardly extending tongue insufficient to carry the cur-

rent, resulting in sputtering or frying at the leading edge, which contacts the electrode, and thereby producing secondary contacts, which are extremely undesirable, as well as pitting the face of the electrode.

It will be apparent that this construction provides a narrow angle switch which can be rapidly operated to produce snap action opening and closing of the circuit controlled by the switch.

10 In the form of the invention shown in Figure 2, the switch envelope is adapted to be mounted in vertical position, and is substantially identical in construction with the exception that the envelope 5' has its tubular body portion fore-shortened so that when in vertical position the body of mercury 24', which is of appreciable volume stands at a level closely adjacent the tungsten or similar disc 17. Here again the disc acts as a baffle preventing splashing of the mercury 15 within the envelope, and also serves as the arc 20 resisting medium between which the initial contact is made from the envelope to the electrode through the body of mercury. Such a switch may be used for closing the circuit when the 25 switch is tilted a predetermined amount from a true vertical position, or for a pendulum type switch in which the circuit is made at opposite ends of its swing with the disc 17 serving as a baffle for preventing surging movement of the 30 mercury, which might result in secondary contacts.

Considering now the switch shown in Figure 3, there is provided a switch envelope 30 having a counterbored portion 32 in which is pressed a 35 ceramic insulating member 33 provided with a central bore. Extending through this bore is a tungsten electrode 34 having the inwardly projecting end 35 adapted to be engaged by the body of mercury 36 within the envelope 30 when the 40 switch is tilted. The electrode 34 is provided with a shouldered portion 37 seating against the rear face of the ceramic bushing 33, and is held in position by means of the resilient compression gasket 38 fitting about the shoulder and against the 45 rear face of the ceramic 33, which is radially expanded into sealing engagement by means of the ceramic compression member 39 which, if desired, may also be formed of hard rubber or the like and which is provided with the extending reduced cylindrical portion 40 radially insulating the 50 projecting shank of the electrode 34 from the spun-over end 24 of the envelope which locks the retaining ring 43 and the sealing means in compressed position. A suitable conductor 44 is secured to the end of the electrode 34 and a second conductor 45 is electrically and mechanically bonded to the envelope 30. A suitable sealing cement or other sealing compound 46 is applied over the end of the envelope about the conductors 44 and 45, embedding them in position to relieve any stresses upon the connections to the electrode and the envelope. Over the external surface of the envelope there is applied an insulating case 47 which may be formed of wood, fiber or molded rubber, or the like, and which has a closed end portion 48 provided with the openings 49 through which the conductors 44 and 45 are led out. The opposite end of the case 47 is open and the case is sealed against displacement from the envelope by means of sealing material 50 disposed in the open end thereof, thereby locking the envelope within the case. In this form of the invention the entire 60 electrode 34 is made of a high arc-resisting material, such as tungsten or molybdenum, and 65 70 75

consequently provides a low resistance contact through the switch without any danger of deterioration of the electrode surface even though the switch be of a type which is unevacuated and which is not provided with a reducing atmosphere or a liquid fill.

In Figures 4 to 8, modified types of switches are provided, all employing the same principle of a high arc-resisting electrode within a metal envelope. Similar parts are indicated by similar reference numerals throughout these figures. In Figure 4 a metal envelope 50 is provided having the enlarged end 52 provided with the internal shoulder 53 against which is seated the ceramic 54. The ceramic 54 is provided with a cup-shaped recess 55 through which projects the tungsten or molybdenum electrode 56. A suitable body of mercury 57 is provided in the envelope 50 and when the switch is tilted, flows into position to make contact between the envelope 50 and the projecting electrode 56. The electrode has its outer end projecting through a bore in the ceramic 55, and is provided with an annular groove 58, this end of the electrode extending into the recess 59 of the terminal member 60, which may be formed of steel, pure iron, or the like. The terminal member 60 is held in position in the recessed end of the ceramic 54 by means of a resilient compression gasket 62, which is pressed against the shouldered head 63 of the terminal member by means of the compression member 64 formed of rigid insulating material, such as a ceramic, hard rubber, or the like, the entire assembly being held in compressed engagement by means of the retaining washer 65 and the spun-over end 66 of the envelope. The electrode 56 is held in the bore of the head 63 of the terminal member 60 by staking over a portion of the terminal member at the outer end of the bore, as indicated at 67, into the annular groove 58. This firmly locks the molybdenum or tungsten electrode in place and provides a unitary assembly.

If desired, the interior of the switch chamber may be evacuated through the tubulation 68, which is then pinched and welded closed to provide either a vacuum in the switch chamber, or the switch chamber may be filled with an inert gas under pressure through the tubulation, as described in detail in the copending application of Paul S. Bear, Serial No. 293,690, filed September 7, 1939.

In Figure 5 a similar construction is provided except that the electrode 70 is provided with a threaded end 72 which is threaded into a recess formed in the head portion 73 of the terminal member 74. This also locks the electrode in position since after the electrode has been threaded into position, the end of the terminal member 74 is ring staked about the threads to prevent displacement of the electrode, as indicated at 75. The electrode 70 in this form of the invention may be either molybdenum or tungsten.

In Figure 6 a still further modified form of construction is provided in which the electrode 76, which, in this form must be formed of molybdenum, is welded as indicated at 77 into a recessed portion in the head end 78 in the terminal member 79. The nickel welding material must be on the end of the electrode 76, as shown, the recess in the head 78 of the terminal member having a concave bottom to accommodate this welding material. This firmly secures the electrode in position and provides a very compact and easily assembled construction.

In Figure 7 a still further modification of the switch structure is provided in which the electrode 80 extends into a recess 82 in the terminal member 83, and is held in place by having a shrink fit in this recess to compress the head portion 84 of the terminal member 83 about the outer end of the electrode 80. With such a shrink fit, displacement of the electrode is not possible inwardly, and thus a unitary joining of the electrode 80 and terminal member 83 is provided.

In the forms of the invention shown in Figures 3 to 7, it is imperative that the radial clearance between the electrode and the internal wall of the envelope be not greater than .122 inch and not less than .062 inch. The purpose of such a clearance is to insure that the body of mercury will readily flow into the annular space between the electrode and the envelope, and this clearance must be less than the meniscus height of the mercury in order to effect positive contact as the movable body of mercury engages the electrode. If too small a radial clearance is provided, the body of mercury will be blocked from flowing into any substantial contact with the annular surface of the electrode, and only point contact will be effected. It is therefore essential that the radial clearance be maintained within the limits specified.

In the form of the invention shown in Figure 8, the envelope 50' is provided with a counterbored portion providing the radial shoulder 85 against which the ceramic 86 is engaged. The ceramic 86 is provided with an enlarged outwardly opening recess 87 within which is disposed a cold rolled steel electrode head 88 which is axially recessed in an opposite direction to receive the outer end of a tungsten electrode 89 projecting through the ceramic 86 and extending into the recessed portion of the electrode head 88. The tungsten electrode is provided with an annular groove 90 which is ring staked to the electrode head 88 as indicated at 92. This provides a very compact electrode structure in which the electrode head 88 terminates substantially in the same radial plane as the outer end of the ceramic 86. The terminal connection to the electrode head 88 is provided by a spring steel disc 93 which has pressure contact with the outer radial face of the electrode head 88 being held thereagainst by the molded rubber gasket 94 compressed tightly thereagainst by means of the retaining washer 95 and the spun-over end 96 of the envelope. The disc has connected thereto the terminal conductor 97 which is soldered or brazed to the disc as indicated at 98, and is provided with the insulating covering 99 protecting the conductor 97 from possible radial flash-over to the ring 95 and end 96 of the envelope. With this construction a switch suitable for snap action may be provided and, if desired, the switch may be evacuated and filled with an inert gas by means of tubulation 100, although this is not essential. For snap action, the amount of mercury shown would be increased since the operating angle of the switch would not be important under such conditions.

It is therefore believed apparent that we have provided a relatively economical switch construction which may be either of the unpumped or the evacuated type, and in which the end assembly is simplified, while yet providing for a high arc-resisting metal contact so that the mercury directly contacts the arc-resisting elec-

trode, which may be of tungsten or molybdenum, and no retained body of mercury is required.

We are aware that a number of changes may be made in certain of the details of the present construction, and we therefore do not intend to be limited except as defined by the scope and spirit of the appended claims.

We claim:

1. A mercury switch comprising a cup-shaped metal shell having a ceramic insert in the open end thereof, a frusto-conical recess in said insert, an electrode closing the small end of said recess and having an externally projecting shank extending axially inwardly through said recess beyond the inner end of said insert, an electrode disc of arc resisting metal carried on the inner end of said shank in radially spaced relation to said shell, said disc being solid and having its periphery spaced from said shell a distance less than the meniscus height of mercury and a body of mercury in said shell adapted to contact said disc to close the circuit through said switch and movable past said disc through said recess into contact with said electrode.

2. A mercury switch comprising a cup-shaped metallic envelope having a radial shoulder adjacent the open end thereof, a refractory insert seated in said end against said shoulder and having an axially extending bore therethrough, an electrode having a radially flanged portion seated in and closing the outer end of said bore and having an axially projecting shank extending outwardly of said envelope and a second shank extending inwardly thereof beyond said shoulder, means forming a resilient seal about the outer radial faces of said electrode flange and insert, an electrode baffle disc on the inner end of said shank radially spaced from the envelope and formed of an arc-resisting metal, and a body of mercury in said switch adapted to bridge between said disc and envelope to close a circuit therebetween and thence movable into contact with said shank and flange, said disc thereby taking any arcing occurring during make or breaking of contact.

3. The switch of claim 2 wherein said disc has its periphery spaced laterally from the in-

terior of said envelope a distance less than the meniscus height of the mercury to insure that initial making and final breaking of contact occurs on said disc.

5. In a mercury switch, a cup-shaped metallic switch envelope having an internal shoulder adjacent the open end thereof, a ceramic seated against said shoulder and having an outwardly facing axial recess, a terminal member having a head end seated in said recess, an electrode shank of arc-resisting metal secured in said head end and extending axially inwardly through said ceramic, said shank terminating at its inner end in a radial disc of arc resisting metal radially spaced from said envelope wall, sealing means for sealing said ceramic and terminal member in the open end of said envelope and a body of mercury in said envelope adapted to make and break the circuit with said terminal member by initial contact with said disc.

10. 4. The switch of claim 4 further characterized in that the radial distance between said envelope and the periphery of said disc lies in the range between 0.062" and 0.122".

15. 5. The switch of claim 4 further characterized in that the axial inner face of said ceramic has a concave recess therein about said prong to increase the exposed lateral surface of said prong and to form a stop for said mercury body.

20. 6. The switch of claim 4 further characterized in that the axial inner face of said ceramic has a concave recess therein about said prong to increase the exposed lateral surface of said prong and to form a stop for said mercury body.

25. 7. In a mercury switch, a cup-shaped metallic switch envelope having an internal shoulder adjacent the open end thereof, a ceramic seated against said shoulder and having an outwardly

30. facing axial recess, a terminal member having a head end seated in said recess, an electrode

35. prong secured in said head end and extending axially inwardly through said ceramic sealing means for sealing said ceramic and terminal member in the open end of said envelope, said terminal member terminating short of said open end, and a terminal conductor having resilient contact means at its end held against the terminal member by said sealing means.

40. 45. CHARLES W. TRAUTMAN.
HERBERT E. BUCKLEN, III.
